FIG.6

FIG. 1 is a front elevation of a handle for flatware showing my new design;

FIG. 2 is a side elevation;

FIG. 3 is a rear elevation;

FIG. 4 is a top plan view;

FIG. 5 is an enlarged transverse section taken on line 5—5 of FIG. 1; and

FIG. 6 is an enlarged transverse section taken on line 6—6 of FIG. 1.

I claim:

The ornamental design for a handle for flatware, as shown and described.
